WASH FOUNTAIN

Brooks Stevens, Fox Point, Wis., assignor to Bradley Washfountain Co., Milwaukee, Wis., a corporation of Wisconsin

Application September 26, 1958, Serial No. 52,783

Term of patent 14 years

(Cl. D4—2)

Fig. 1 is a view in perspective of a wash fountain showing my new design;

Fig. 2 is a side view in elevation of my new design;

Fig. 3 is a front view in elevation of my new design; and

Fig. 4 is a top view of my new design.

I claim:

The ornamental design for a wash fountain, as shown.
